UNITED STATES PATENT OFFICE.

WILLIAM HENRY SHUMAKER, OF MIAMI, FLORIDA.

HOLDER FOR CAR REPLACERS.

Application filed April 8, 1922. Serial No. 550,733.

To all whom it may concern:

Be it known that I, WILLIAM H. SHUMAKER, a citizen of the United States, and resident of Miami, in the county of Dade and State of Florida, have invented certain new and useful Improvements in Holders for Car Replacers, of which the following is a specification.

My invention relates generally to car replacers, more particularly to devices for holding a replacer in applied position with respect to a rail, and it consists in the combinations, arrangements and constructions herein described and claimed.

10 An object is to provide a holder which is adapted to be applied to railway rails of any ordinary size and to car replacers of a plurality of types of construction and of different shapes and sizes to effectively hold 15 the replacer with which associated in a desired position in respect to a rail.

A further object of my invention is to provide a holder of the character described which is adapted for application to a plurality of car replacers of ordinary construction without any change being required in the construction of the latter and which is adapted to be operatively applied to certain other replacers of ordinary construction 20 with but slight change in the construction 25 of the latter being required.

A further object of my invention is to provide a device of the character described which has means for engaging a rail and a replacer to which applied in such manner 30 as to prevent movement of the replacer relatively to the rail in service and to reinforce the replacer at the point at which the stresses received in service are greatest, 35 thereby preventing the distortion of the replacer on account of the stresses to which it 40 is subjected.

Other objects and advantages will be apparent from the following description, and 45 the novel features of the invention will be particularly outlined in the appended claims.

My invention is illustrated in the accompanying drawings, forming a part of this application, in which

50 Figure 1 is a plan view, showing a portion of a railway track having the invention applied to the rails thereof,

Figure 2 is a side elevation of the structure shown in Figure 1,

55 Figure 3 is a transverse section through

the rails of the track exhibited in the preceding views and through the rail replacers applied thereto, the embodiment of the invention being shown in side elevation, and

Figures 4 and 5 respectively are an enlarged perspective view showing an element 60 of the embodiment of the invention, and a similar view showing a key comprised in the embodiment of the invention.

Referring now to the drawings, I show 65 therein for the purpose of illustration a practical embodiment of the invention and the application thereof. A portion of a railway track includes spaced apart rails 1, 1 mounted upon ties 2 and being provided 70 with car and locomotive replacers 3 which rest upon the ties and are secured to the rails by means embodying the invention, which means will now be described.

The holder illustrated in the drawing and 75 embodying the invention in the form now preferred by me comprises a longitudinal body 4 of flat bar-like conformation and being made of any material having the requisite strength, such as steel or the like. 80 The body 4 is fashioned to provide an end portion 5 which is bent or curved upwardly and rearwardly at its extremity, as indicated at 6 to provide a portion adapted to embrace the edge portion of the base flange 85 7 of a rail. The portion 5 of the body is substantially straight from its juncture with the flange engaging portion 6 to a point intermediate of the length of the body and for a distance greater than the width of 90 the base flange 7. The portion 5 is then merged into a portion 8 which is curved upwardly and then forwardly and merged into a substantially straight end portion 9 which 95 therefore is inclined in respect to the portion 5. The end portion 9 is provided with a slot 10 adjacent to its extremity, which slot 10 extends longitudinally of the portion 9.

A key 11 adapted to cooperate with the slot 10 is curved uniformly for its entire 100 length and is tapered from one end thereof to the other, thus providing curved walls 12 and 13 which converge toward the lower end of the key. The key 11 is provided with a forwardly extending lug or enlargement 14 on the wall 13 at the larger end of the key which enlargement is beveled at 15 at its upper edge and is fashioned to provide a lower side or face 16 which extends substantially at right angles to the upper por- 105 110

tion of the side 13 to which it is joined. The key 11 is beveled at its smaller end, as indicated at 17.

From the foregoing description of the various parts of the device, the operation thereof may be readily understood. The replacers 3 are of a well known type of construction and each includes a front side 18 and a back side 19, the front and back sides being joined together at their upper ends and being downwardly divergent or inclined in respect to each other. The back side 19 is provided with the usual opening 20 which is formed therethrough intermediate of its length and at an appreciable distance from its lower end.

The body 4 is arranged so that the portion 6 embraces the edge of the base flange of a rail and the replacer is arranged adjacent to the opposite edge of the base flange of the rail so that the front side of the replacer rests upon the portion 5 of the body adjacent to the juncture of the latter with the curved portion 8. The portion 9 will then be partially disposed between the front and back portions of the replacer and will extend through the opening 20 of the back side of the replacer so that the lower end of the key 11 can be projected through the slot 10 with the curved wall 12 of the key in contact with the outer face of the rear side of the replacers. It is to be observed at this point that the curvature of the portion 8 is such that the end portion 9 extends substantially at right angles to the rear side of the replacer and it will therefore be obvious that the replacer will be securely held against the base flange of the rail when the key is driven through the slot sufficiently to occasion a desired pressure and camming action on the rear side of the replacer. Since the key 11 is curved, the frictional engagement of the wall 13 thereof with the outer end of the slot 13 tends to hold the key in any position to which driven. Since the key is tapered, replacers of different sizes and shapes may be held effectively against rails of any ordinary size when my improved holder is applied. When it is desired to remove the key, it may be readily pried loose from a position in which engaged with the slot by means of a bar, or like tool, arranged to engage the face 16 of the projection or enlargement 14 at the upper end of the key.

The curved portion 8 extends above the plane of the lower edge of the front side of the replacer and thus serves to resist any appreciable movement of the front side of the replacer toward the rear side thereof, thus tending to prevent any distortion of

the replacer on account of stresses received in service.

Obviously, my invention is susceptible of embodiment in forms other than that in which illustrated in the accompanying drawings and I therefore consider as my own all modifications and adaptations thereof which fairly fall within the scope of the appended claims. 70

Having thus described the invention, what I claim is:

1. The combination with a car replacer having oppositely inclined downwardly divergent front and rear sides and having an opening formed through the rear side above the level of the lower edge of the front side, of a device for holding the replacer in applied position in respect to a rail, said device comprising a longitudinal body having means at one end for embracing an edge portion of the base flange of a rail and being of a length to underlie the base flange of the rail when disposed transversely thereof and to extend beneath the front side of the replacer and through the opening of the rear side of the replacer to project rearwardly thereof substantially at right angles to the rear side, said rearwardly projecting portion having a slot formed therethrough, and a curved key engaging the slot and the rear side of the replacer to hold the latter against movement relatively to the rail. 90

2. The combination with a car replacer having oppositely inclined downwardly divergent front and rear sides and having an opening formed through the rear side, of a device for holding the replacer in applied position in respect to a rail, said device comprising a longitudinal body having a horizontal portion provided with means at one end for embracing an edge portion of the base flange of a rail and being of a length to underlie the base flange of the rail when disposed transversely thereof and an inclined portion into which the horizontal portion is merged at a distance from the other edge portion of the base flange of the rail substantially equal to the thickness of the front side of the replacer at the lower edge of the latter, said inclined portion being of a length to extend between the front and rear sides of the replacer and through the opening of the rear side of the replacer to project rearwardly thereof, said rearwardly projecting portion having a slot formed therethrough, and a curved tapered key engaging the slot and the rear side of the replacer to hold the latter against movement relatively to the rail. 110

WILLIAM HENRY SHUMAKER.
